(57) **CLAIM**

The ornamental design for a cosmetic container as shown and described.

DESCRIPTION

FIG. 1 is a front perspective view of a first embodiment, where the cosmetic container is in a closed condition.

FIG. 2 is a front elevation view of the cosmetic container of FIG. 1.

FIG. 3 is a rear elevation view of the cosmetic container of FIG. 1.

FIG. 4 is a right side view of the cosmetic container of FIG. 1.

FIG. 5 is a left side view of the cosmetic container of FIG. 1.

FIG. 6 is a top view of the cosmetic container of FIG. 1.

FIG. 7 is a bottom view of the cosmetic container of FIG. 1.

FIG. 8 is a front perspective view of a second embodiment, where the cosmetic container is in a closed condition and the top dome portion is transparent.

FIG. 9 is a front elevation view of the cosmetic container of FIG. 8.

FIG. 10 is a rear elevation view of the cosmetic container of FIG. 8.

FIG. 11 is a right side view of the cosmetic container of FIG. 8.

FIG. 12 is a left side view of the cosmetic container of FIG. 8.

FIG. 13 is a top view of the cosmetic container of FIG. 8; and,

FIG. 14 is a bottom view of the cosmetic container of FIG. 8.

The appearance of any portion of the cosmetic container shown with dashed lines forms no part of the claimed design.

1 Claim, 10 Drawing Sheets
